DECOLORIZING AND DEWAXING PETROLEUM LUBRICATING OILS

Claude F. Tears, Mountain Lakes, N. J., assignor to The Petroleum Processes Corporation, Wichita, Kans., a corporation of Kansas

Application January 27, 1934, Serial No. 708,608

2 Claims. (Cl. 196—18)

This invention relates to the removal of color and wax from lubricating oils and one of the important objects of the invention is to combine these two distinct operations in a single process.

5 In conventional refinery practice, the lubricating oil fractions are usually divided into two portions, wax distillate forming the lighter portion and cylinder stock or steam refined stock, the heavier portion. In some instances, the total 10 lubricating oil fraction is handled as one in what is known as the "long residuum" operation. In both methods, the various oil fractions are dewaxed and decolorized by separate processes.

In the practice first outlined, the wax distillate 15 is usually chilled and pressed through high pressure plate filters to remove the wax. This operation is only partly effective, making it necessary to "double press" with lower temperature on the second pressing, to produce a light lubricating oil of low pour test, e. g. 0° F. to 5° F.

After de-waxing, the wax distillate is fractionated to gas oil and light and heavy neutral oils. These neutral oils are then usually decolorized by fuller's earth in percolation filters.

25 The heavier cylinder stock or steam refined stock portions of the first method or the so-called "long residuum" of the second method are usually de-waxed by centrifuging or cold settling. The decolorization of these stocks also is a separate 30 step, but usually performed before the de-waxing. Such decolorization may be either by percolation or contact filtration.

In the percolation method, the heavy lubricating oil is dissolved in light naphtha and 35 pumped through percolation filters containing beds of fuller's earth or other decolorizing medium.

The contact method involves mixing fine fuller's earth, of 200 mesh or the like, or other decolorizing agent with the oil, usually in naphtha solution and usually at elevated temperatures. In some instances, the clay is mixed with the oil and the mixture heated and then cooled before mixing with naphtha. The whole mixture is 45 then passed through a filter press in which the fine decolorizing medium is filtered out of the solution.

If the de-waxing is to be effected by centrifuging, the naphtha solution is chilled slowly under 50 controlled temperatures and chilling rates to promote wax solidified as necessary to enable removal of the wax as petrolatum by centrifugal force and the cold mixture is then centrifuged to effect removal of the wax as the heavier portion.

55 De-waxing by cold settling involves chilling

the naphtha solution below the solidification point of the wax and settling the wax out of the mixture as petrolatum in large settling tanks over long periods of chilling and settling.

In both centrifuge and cold settling methods, 5 the naphtha solution is distilled at relatively high temperatures to remove the naphtha and recover the lubricating oil fraction as a residual product.

Both cold settling and centrifuge processes are 10 inefficient and expensive methods of wax removal, demanding excessive refrigeration for acceptable de-waxing, because of the long spread required between the chilling temperature and the pour test obtained. Furthermore, the petrolatum of both operations contains a high percentage of 15 lubricating oil, ranging from 25% to 75%, depending upon the system employed and the pour test of the oil finally produced.

In addition to the conventional practices outlined, de-waxing has been accomplished by 20 dissolving the lubricating oil stock in propane or similar normally gaseous petroleum hydrocarbon at slightly elevated temperatures and under sufficiently high pressure to keep the solvent in the liquid state. This solution is cooled as by water 25 coolers and exchangers and final temperature reduction to that required for crystallization of the wax is effected by evaporating part of the solvent under reduced pressures. The wax and oil solution are then separated by filtration through mechanical filters. This process requires careful 30 control of chilling rates and solvent ratios to promote the proper wax crystal growth that will permit filtration of the wax by mechanical filters.

35 Decolorization has been accomplished by the use of fuller's earth or other decolorizing medium with the oil in solution in liquid propane or the like. This process is disclosed in the Tears patent application Ser. No. 679,073, covering both contact and percolation methods of filtration.

40 In the present invention, both decolorization and de-waxing are effected in the same operation. In the present disclosure, this is accomplished by a combination of contact filtration and de-waxing in propane or solvent of like nature. De- 45 colorizing clay is mixed in a propane-oil solution, the mixture is chilled by flash evaporation of part of the propane and the wax thereby solidified is filtered out of the propane-oil solution, using the decolorizing medium to assist the wax removal. 50 The wax-clay component is then washed with cold propane to free it of retained oil-propane solution and warm propane is then used to melt and flush the wax out of the decolorizing clay. The oil-solvent and wax-solvent portions are sepa- 55

rately stabilized and stripped and the de-oiled and de-waxed decolorizing medium is removed from the system as a part of the clearing of the filter.

Various other novel features of the invention 5 will appear as the specification proceeds and will be apparent from consideration of the accompanying drawing, which represents a flow sheet diagram of one practical method of carrying out the invention. This showing is primarily illustrative and is to be so considered, the claims defining the broad scope of the invention.

In the diagram, the lubricating oil stock which is to be decolorized and de-waxed is transferred from a storage tank 1, to an agitator 2, by a 15 pump 3.

The agitator is indicated as of the mechanical mixer type and is shown equipped with heating coils 4, by which the oil may be brought up to a temperature best suited to the removing of 20 color.

In the present disclosure, the decolorizing clay is introduced at 5, into the oil, warmed and in course of agitation in the agitator, this being a desirable method of getting the necessary contact of oil and clay for decolorization, but it is within the scope of the invention that the decolorizing medium be introduced in the system with the solvent or with the solvent-oil solution.

The warm oil-clay mixture is transferred from 30 the agitator by pump 6, to a mixer 7, and there it is combined with liquid propane or like solvent from storage tank 8, transferred to the mixer by pump 9.

To assure thorough mixing of clay, oil and 35 propane, the mixture may then be passed through a heater 10.

With mixing and dissolving of the oil in the solvent properly accomplished, temperature reduction may be initiated as by passing the mixture through a suitable cooler indicated at 40 11.

The mixing system, which may be considered as including the heater, and the cooler are all closed in to keep pressure sufficient to hold the propane or like solvent in the liquid state. This 45 is effected in the illustration by a back pressure valve 12.

Final chilling sufficient for solidifying wax in the mixture is effected, in the present disclosure by expansion of the mixture into a flash chiller 50 13, the back pressure valve being set usually to effect a reduction to atmospheric pressure in this chiller. This reduction of pressure and evaporation of propane produces a lowering of temperature to -45° F., the equilibrium temperature at 55 atmospheric temperature. If higher temperature is permissible under the circumstances, the flash chiller is vented to correspondingly higher pressures.

To keep the wax and clay suspended in the mixture and prevent them from settling out in the flash chiller, there is provided in the illustration a perforated coil 14, in the bottom of the chiller, which can be supplied with gaseous propane through line 15, from the top of the 60 propane storage tank. This agitation also aids in the solidification and the separation of wax from the oil solution.

The propane vapor released from the top of the flash chiller by valve 16, is saved and re-used by passage through line 17, to compressor 70 18, condenser 19 and line 20, to liquid propane storage tank 8. Baffles 21, in the chiller prevent entrainment of liquid with this vapor on the way back to storage.

75 The chilled mixture of wax, decolorizing clay

and oil-propane solution is taken from the bottom of the flash chiller and transferred by pump 22, to filters 23, 24, which usually through valve connections 25, 26, are alternated, one filtering while the other is being washed and cleaned. 5

These filters are of the pressure type, to hold the solvent in the liquid phase and in them, the decolorizing clay and solidified wax portions of the mixture are filtered out of the oil-propane solution, the clay and wax being retained on 10 the filter plates and the oil-propane solution passing through, into the outer shells of the filters shown.

The decolorizing clay in mixture with the wax crystals forms a filter cake that will not mat or 15 plug as does wax alone. Furthermore, the time required for formation of this cake is less, because of the clay present, reducing or eliminating the amount of oil that might require "slopping" because of high wax content. 20

The filtrate, the oil-propane solution, decolorized and de-waxed passes out through line 27, to oil stabilizer 28, where propane is distilled off under pressure and passes through line 29, to condenser 19 and thence through 20, to propane 25 storage tank 8. The partially stripped oil discharges from the bottom of the stabilizer through line 30, to oil stripper 31, where remaining traces of propane are distilled off under pressure due to suction of the compressor, this stripper being 30 indicated as connected at the top by line 32, with the suction side of the compressor.

The wax and clay mixture on the filter plates is washed with cold propane to remove traces 35 of oil, by operating pump 33, to force cold propane from tank 34, through valved connections 35, 36, to the filters, after cutting off the flash chiller connections at 25, 26.

The cold wash propane is prepared in the present disclosure by expanding liquid propane from 40 storage pressure, coming through line 37, to the compression line suction pressure, by means of expansion valve 38, opening into the cold storage tank 34. The head of this tank is shown connected with the compressor suction line 17, by a 45 valved line 39, and baffle assemblies 40, are shown in this tank for preventing entrainment of liquid in the vapor passing off to the compressor.

This cold stored liquid propane is at approximately the same temperature as the mixture in 50 the flash chiller. Washing the wax and clay on the filter plates with this cold propane removes traces of oil held in the filter cake. The wash liquor may be passed through the valved lines 27, 55 to the oil stabilizer, where the propane can be distilled off and returned to storage and the oil be collected as a residue and stripped as above described.

After being washed of oil, the filter cake is 60 washed with warm propane taken from storage by pump 41 and heated at 42, sufficiently to melt and re-dissolve the wax in the wax-clay mixture, this heated propane being delivered into the filters through valved lines 43, 44.

The solution of wax and warm propane is taken off from the filters through valved lines 45, to wax stabilizer 46, where propane is distilled off under pressure, passing through lines 47, 29, to the propane condenser and storage and the wax 70 passing off at the bottom at 48, to the wax stripper 49, from which propane passes off through 50, 32, to suction side of the compressor.

The stripped lubricating oil decolorized and de-waxed is run down to storage at 51, and wax 75

freed of oil and decolorizing clay and stripped of solvent is run down to storage at 52.

The decolorizing clay, washed of oil and denuded of wax, may be removed from the filter, 5 in the illustration, by taking the filter assembly out of the pressure shell and scraping the clay off the plates. Before opening the filters, the shells may be vented to the compressor suction through valve lines 53, 54, to remove propane from 10 the filter cake. This leaves the clay substantially dry and easily removable. If desired, the clay may be washed with a color removing solvent, such as trichlorethylene, before or after removal from the filter, for re-use, but in view of the economies 15 effected by the process, it may simply be discarded or put to other uses.

Filters of the edge or continuous types which effect continuous removal of cake and washing of the cake may be employed, with provision for 20 pressure to keep the solvent liquid.

The effectiveness of the process may be indicated by way of a specific example, in which long range distillate of lubricating oil from Mid Continent crude having a viscosity of 400 seconds 25 Saybolt at 100° F. was dewaxed and decolorized as described above, using an acid treated decolorizing clay in the proportion of 1/4 lb. per gallon of charge, mixed at 110° F. and the flash chiller vented to atmospheric pressure. The finished oil 30 had a color of 3 1/2 N. P. A. and a pour test of -10° F. with no cloud showing at that temperature.

The process has all the advantages of a propane dewaxing process and those of a propane decolorizing operation and special advantages that 35 neither of these possess, including that of a combination of all in one economical unit.

It will be apparent that the process is particularly well suited to handle "long residuum" or 40 total "lube distillates", because it can be operated so economically and because all grades of wax can be removed, the different wax structures in the several fractions of the oil being all handled without difficulty.

45 Higher yields of lubricating oils are obtained because of washing the oil from the wax with cold propane, while the wax is held on the filter plates. The presence of the decolorizing clay makes this possible and feasible because the filter cake does not mat as when filtering wax alone. For these same reasons, the wax produced has a higher melting point and a lower oil content.

The process requires no such close attention 50 to solution ratios and chilling rates as in known propane dewaxing processes. Satisfactory operation, for example, is obtained using the flash chilling, with propane contents varying between 35% and 85%, after chilling.

The process is suited to the handling of short 55 range wax distillates, that is, wax distillates which do not contain the large amounts of gas oil required in normal refinery practice for the control of crystal growth. This is because in the present process, the crystal growth is not so important 60 and vital an item and is taken care of more readily because of the presence of the decolorizing clay.

While refrigeration by vaporization of the propane is practical and desirable, this is not essential 65 as indirect chilling of the propane solution or a combination of indirect chilling and chilling by evaporation, may be employed.

Another important feature is that none of the 70 decolorized and de-waxed oil need be subjected to temperatures above 200° F. or that required to remove the propane from the oil. The deleterious

effects of high temperature distillation used in re-running neutrals and stripping naphtha from heavy oils are therefore avoided.

The cost of clay is reduced by the invention, because the oil-propane solution has such low viscosity, serving to increase the activity of the decolorizing medium. The effective usefulness or life of the clay is thus extended. 5

The presence of the decolorizing clay in the filter, in mixture with the wax crystals, minimizes 10 the care, control and time required to produce a filterable wax mixture and because of the fact that the filter cake so formed does not mat, the propane-oil solution may be passed through at long maintained high filter rates. 15

The fact that wax crystal growth control is minimized makes it possible to carry on a continuous chilling operation, with rapid flash evaporation of the propane for refrigeration.

The presence of the decolorizing clay permits 20 the removal of the wax at higher temperatures than would be possible without the clay, because with the clay the filter surface is made more effective for wax removal. This has the ultimate effect of lessening the amount of refrigeration required 25 to produce an oil having a desired low pour test.

The combination of the two decolorizing and dewaxing operations as disclosed, enables the utilization of much common equipment and avoids the expense of duplicating various units. 30 This is particularly true of the filtration units which serve the dual purpose of separating the decolorizing medium and the wax from the propane-oil solution.

Also in the invention, the oil-solvent ratio is 35 not critical and need not be kept constant. The propane vapor introduced for agitating and keeping the decolorizing clay and wax in suspension in the flash chiller may be controlled as a means for compensating for the amount evaporated or 40 for varying or otherwise governing the oil-solvent ratio.

While propane has been given as an example of a solvent suitable for the carrying out of the process, it will be appreciated that other solvents 45 of like character might be substituted and this expression, as well as others employed herein are therefore to be construed in a descriptive rather than in a limiting sense, except possibly as limitations may be imposed by state of the prior art. 50

What is claimed is:

1. The herein disclosed process of decolorizing and dewaxing petroleum lubricating oils in one continuous operation which comprises mixing comminuted adsorbent decolorizing medium with 55 the lubricating oil, mixing normally gaseous liquefied hydrocarbon solvent with said mixture of lubricating oil and decolorizing medium, heating the whole mixture to effect substantially complete solution of oil and wax in the solvent, cooling to 60 remove added heat, flash vaporizing sufficient of the normally gaseous liquefied hydrocarbon to chill the remaining mixture to wax solidification temperature, filtering the oil-solvent component from the wax-decolorizing medium component 65 and separately recovering the solvent from the oil-solvent component and the wax-decolorizing medium component.

2. The herein disclosed process of decolorizing and dewaxing petroleum lubricating oils in one 70 continuous operation which comprises mixing comminuted adsorbent decolorizing medium with the lubricating oil, mixing normally gaseous liquefied hydrocarbon solvent with said mixture of lubricating oil and decolorizing medium, heating 75

the whole mixture to effect substantially complete solution of oil and wax in the solvent, cooling to remove added heat, flash vaporizing sufficient of the normally gaseous liquefied hydrocarbon to chill the remaining mixture to wax solidification temperature, filtering the oil-solvent component from the wax-decolorizing medium component, washing the wax-decolorizing medium component retained in the filter with fresh cold solvent to

remove traces of oil, dissolving the wax from the wax-decolorizing medium component by washing in situ with fresh warm solvent, drying the filtered decolorizing medium by reducing the pressure on the filter thereby vaporizing the normally gaseous liquefied hydrocarbon solvent therein and separately recovering the solvent from the oil and wax components.
